UNITED STATES PATENT OFFICE.

CHARLES LALOR BURDICK, OF NEW YORK, N. Y., ASSIGNOR TO GUGGENHEIM BROTHERS, OF NEW YORK, N. Y., A COPARTNERSHIP.

REFRIGERATING APPARATUS.

Application filed June 18, 1925. Serial No. 37,924.

This invention relates to refrigerating apparatus of the type wherein the cooling effect results from the vaporization of an appropriate refrigerating medium or refrigerant, and, more particularly, the object of the invention is to provide an apparatus by means of which liquids may be cooled in a particularly effective manner.

In the operation of refrigerating plants an appropriate refrigerant such as a liquid having a low boiling point, for example, ammonia, is allowed to vaporize or evaporate in an apparatus which is arranged to absorb heat from the liquid which it is desired to cool. The vaporized refrigerant is removed from the evaporating chamber, again liquefied by compressing and cooling, and then returned to the evaporating chamber.

All of this apparatus as usually constructed, namely the evaporating device, the compressors and the condensers are large massive pieces of apparatus, relatively expensive to manufacture and install, and occupy a relatively large amount of space. In the construction of this apparatus, it is of great importance that all of the material used be employed to the best advantage so as to produce the most effective results, and this is of particular importance in the construction of the evaporating device. The present invention aims to provide an evaporating device in which all of the material which enters into its construction is employed in a particularly effective manner, thereby reducing the amount of material used, the weight and the cost of the apparatus.

In accordance with the invention the cooling apparatus comprises a container for receiving the liquid refrigerant and the liquid to be cooled, this container being provided with appropriate internal walls forming means for separating these liquids. Appropriate means are provided for supplying liquid refrigerant to this container and for withdrawing the vaporized refrigerant therefrom, and means are also provided for maintaining on substantially the entire surface of the separating means a film of liquid refrigerant undergoing vaporization. By maintaining this film of liquid refrigerant undergoing vaporization over substantially the entire surface of the separating wall, the heat from the liquid to be cooled causes the vaporization of the utmost possible amount

of the refrigerating liquid, and thus a high rate of cooling is produced.

The apparatus conveniently comprises a vaporizing chamber for the liquid refrigerant having a plurality of conduits extending therethrough for the purpose of carrying the liquid to be cooled, and means are provided within the chamber for maintaining a film of liquid refrigerant on substantially the entire surface of these conduits within the chamber. The film of liquid refrigerant is preferably produced through the instrumentality of a plurality of vertically spaced distributing plates or trays upon each of which there is maintained a pool of the liquid refrigerant, these trays having properly formed passage-ways for delivering the liquid refrigerant onto the surfaces of the conduits. The spacing of the liquid refrigerant distributing trays is such that a continuous film of liquid refrigerant undergoes vaporization from one end of the conduits to the other.

In its preferred form the apparatus comprises a vertically arranged cylindrical drum having a plurality of tubes extending from end to end thereof and secured to the top and bottom header plates. These tubes are divided into two groups through which the liquid to be cooled is circulated in opposite directions by suitable means, a compartment being provided below the bottom header for reversing the direction of flow of the liquid to be cooled and conducting it from one group of tubes to the other. There is a tank at the top of the drum having two compartments, one communicating with each group of tubes. The liquid to be cooled is supplied to one of these compartments and withdrawn from the other. The interior of the drum between the top and bottom header plates is provided with a plurality of trays which have perforations through which the tubes pass, these perforations being slightly larger than the tubes so that the liquid refrigerant which is conveyed to one or more of the upper trays and which forms a pool thereon is discharged onto the surfaces of the tubes through these openings. The trays are arranged in staggered relation so that by supplying an excess of liquid refrigerant, the pool overflows from each tray onto the one next below it, thereby supplying liquid refrigerant to all of the trays.

The liquid which is passed through the

tubes of this apparatus for the purpose of cooling the same is, in the ordinary refrigerating plant an ordinary brine solution, but the apparatus is adapted to cool other liquids and in particular solutions from which it is desired to cause the precipitation or crystallization of salts through the lowering of the temperature of these solutions. Thus the apparatus is particularly well adapted for use in connection with the precipitation of sodium nitrate from a solution of caliche by the cooling of such a solution in accordance with the principles of the disclosure in Patent No. 1,516,550 granted on November 25th, 1924 to E. A. C. Smith.

The invention will be better understood by referring to the accompanying drawings in which, by way of example, two modifications of the apparatus of the present invention are illustrated. In these drawings

Fig. 1 is a vertical sectional view showing the preferred form of cooling apparatus.

Fig. 2 is an enlarged fragmentary section showing the distribution of the liquid refrigerant from one of the trays onto the surface of the tubes.

Fig. 3 is a transverse section taken on line 3—3 of Fig. 1.

Fig. 4 is a transverse section taken on line 30 4—4 of Fig. 1.

Fig. 5 is a longitudinal section of a modified form of the apparatus and

Fig. 6 is a transverse section taken on line 35 6—6 of Fig. 5.

Referring now to the accompanying drawings the cylindrical shell 10 of steel plate or other suitable material is provided at the bottom with a header 11 and at the top with a header 12, these headers being flanged and welded or otherwise tightly joined to the interior surface of the shell 10 so as to thereby form a tight vaporizing chamber 13 on the interior thereof. A plurality of tubes 14 of suitable material are expanded as shown at 40 45 15 in Fig. 2 into apertures in the header plates 11 and 12, leaving their open ends in communication with the spaces at the bottom and top of the header plates. It will be understood that the liquid to be cooled is passed through these tubes and the particular way in which this is carried out by the present invention will appear later on.

The interior of the vaporizing chamber 13 is provided with a plurality of vertically spaced horizontal trays 16, these trays being perforated to allow the tubes 14 to pass through them, and being supported in any appropriate manner within the chamber. The perforations in the trays 16 may be seen in Fig. 2 and are somewhat larger than the diameter of the tubes 14, leaving an annular space 17 around each tube.

Pools of liquid refrigerant 18 are maintained on the trays 16, the depth of these pools being determined by the height of rim

members 19 which are provided around the peripheries of the trays. The trays are equipped with these rims in preference to securing the edges of the trays to the interior of the shell 10 in order to facilitate the construction and assembly of the apparatus. In order to form the pools 18, liquid refrigerant is fed to one or more of the trays 16 near the top of the vaporizing chamber. As shown in Fig. 1, liquid refrigerant is supplied to the second tray 16 through a pipe 20.

The liquid refrigerant from pipe 20 collects on the surface of the second tray 16 until it reaches the top of overflow lip 21 from which it is poured onto the surface of the tray next below. The overflow lip 21 of the next lower tray discharges onto the tray below that, and this process is repeated until all of the trays contain pools of liquid refrigerant. It will be understood that the overflow lips 21 of adjacent trays are staggered with respect to one another so that the liquid will be discharged from one tray onto the next as just described. These overflow lips are arranged in spaced relation to the interior surface of shell 10 so as to form a passage-way for the vaporized refrigerant as it proceeds past each of the trays toward the upper part of the vaporizing chamber.

The liquid refrigerant from the several pools 18 flows through each of the annular spaces 17 which surrounds each of the tubes 14 in the form of annular streams 22 which flow down around the outside surfaces of the tubes 14. These annular streams of liquid refrigerant undergo evaporation by the heat from the liquid to be cooled which passes through the walls of tubes 14, and by the time that the annular streams 22 have flowed a certain distance over the tubes 14 they will be completely evaporated. The spacing of the liquid refrigerant distributing trays 16 is however such that this point is in effect never reached but an excess of liquid refrigerant is always distributed through the annular aperture 17 and the spacing of the trays 16 is sufficiently close to provide a film of liquid refrigerant undergoing vaporization on the surface of each of the tubes 14 which is continuous from substantially one header to the other.

The vaporized refrigerant passes upwardly past the staggered discharge lips 21 of the distributing trays 16 and upon reaching the top of the vaporizing chamber 13 takes its exit therefrom through a pipe 23. This pipe conducts the vaporized refrigerant to the compressing and condensing apparatus (not shown) where it is liquefied and then returned to the vaporizing apparatus through the pipe 24 which is the supply pipe for liquid refrigerant.

In order to avoid the possibility of mechanically entrained liquid refrigerant be-

ing carried out through the pipe 23 with the vapor, no liquid refrigerant is fed onto the uppermost tray 16. Although all of the trays 16 act as baffle plates to carry the vaporized refrigerant in a circuitous path through the vaporizing chamber, this uppermost tray and the conduits passing through it serve as a particularly effective means of preventing mechanically entrained liquid refrigerant in the vapor from being carried out through the vapor discharge.

Any liquid refrigerant from the pipe 20 which is mechanically entrained by the vapor as it passes the open end of this pipe, is drawn through the labyrinth of tubes to the right of the discharge end of pipe 20 and those tubes between the uppermost tray 16 and the top header 12. The surfaces of these tubes are comparatively dry because there is no pool of refrigerant maintained on the uppermost tray 16. The contact with these tubes causes the separation and evaporation of all of the mechanically entrained liquid.

Inasmuch as an excess of liquid refrigerant is maintained on all of the trays 16 except the uppermost tray, a certain amount of this liquid will collect on the bottom of the vaporizing chamber 13. Such liquid is removed through pipe 24 by any suitable device such as the pump 25. The liquid refrigerant withdrawn through pipe 24 is discharged from the pump through pipe 26 and returned to the feed pipe 20. In this way a continuous circulation of the liquid refrigerant is maintained.

Thus far the description has dealt entirely with the flow and control of the refrigerating medium or refrigerant and the parts of apparatus which are adapted to control the flow of the liquid to be cooled will now be described. The bottom of the vaporizing tank or chamber 13 rests upon a hollow base structure 27 which is carried on an appropriate foundation 28. The vaporizing tank is preferably joined to the base portion by means of cooperating flanges 29, between which there may be placed an appropriate packing so as to form a liquid-tight joint.

Immediately below the bottom header 11 and carried within the hollow base 27, when required, there is a chamber 30 which has a conical bottom 31. The purpose of this chamber will appear later on. At the top of the apparatus there is provided a receptacle 32 whose side walls may conveniently be formed by extensions of the shell 10 and whose bottom is formed by the top header plate 12 so that this receptacle is in communication with the interior of the tubes 14. This receptacle 32 is subdivided by a central partition 33 into two compartments 34 and 35 and may be either open or closed on top.

Compartment 34 is the entrance compart-

ment for the liquid to be cooled which is flowed into the apparatus through a conduit 36. On the opposite side of receptacle 32 a box-like structure 37 is provided, when required, which is in communication with compartments 34 and 35 through the openings 38 and 39 respectively. Within this box-like structure there is located a pumping device which is indicated generally by the numeral 40 and which is driven by a shaft 41 that extends through one wall of the structure to which power may be applied by the belt 42 operatively connected to a driving motor which is preferably of the variable speed type. By means of this pumping device, liquid is transferred from compartment 35 to compartment 34. The cooled liquid is conveyed from the cooling apparatus through an appropriate conduit such as the launder 43 which opens out of compartment 35.

In operating the apparatus, liquid refrigerant is continuously supplied to the vaporizing chamber 13 through the pipe 20 as previously described, and the portions of the apparatus adapted to receive the liquid to be cooled are completely filled with such liquid up to the level indicated generally by the line 44. With the liquid to be cooled at this level both of compartments 34 and 35 will be well filled with the liquid, together with the interior of the box-like structure 37. The interior of all of the tubes 14 which extend through the vaporizing chamber 13 and the chamber 30 below the bottom plate 11, will also be filled.

The pumping device 40 is now set in operation and produces a circulation of the liquid to be cooled in the direction of the arrows shown in Fig. 3, causing the liquid to flow downwardly through all of the tubes 14 which are in communication with the compartment 34 and into chamber 30. From chamber 30 the liquid starts in an upward direction through the tubes 14 which are in communication with compartment 35. Reaching compartment 35 the liquid returns to the pumping device 40 or passes out of the apparatus through launder 43.

The flow of the liquid to be cooled into and out of the apparatus by way of conduits 36 and 43 respectively is controlled by varying the hydrostatic head of this liquid in any appropriate manner such, for example, as by means of pumps or of suitably arranged weirs. In this way the liquid level is maintained within the apparatus and the liquid is caused to leave the cooling device as soon as the temperature thereof has been lowered to the desired point. If there is no flow of liquid into or out of the apparatus the pumping device 40 will continue to circulate the liquid as described above and the temperature will be continually lowered. The

rate of cooling depends largely on the velocity of the liquid through the tubes 14 which is readily controlled by varying the speed of the driving motor which operates the pumping device 40 or by means of the pump feeding conduit 36. Hence by maintaining the film of liquid refrigerant on the surface of the tubes 14 within the vaporizing chamber 13 which is effected through the means of the liquid distributing trays and the liquid refrigerant circulating means, a maximum cooling effect is obtained. The control of the temperature of the cooled liquid is regulated with facility by controlling the flow of liquid through the conduits 36 and 43 and/or by regulating the speed of the circulating pump 40.

The conical bottom 31 of the chamber 30 is useful when solids are to be precipitated from the liquid undergoing cooling and serves to collect these solids in the form of a sludge around the discharge outlet 45. A valve 46 across this outlet and appropriate operating mechanism including the handle 47 are provided by which, from the outside of the hollow base portion 27, the valve 46 may be opened to allow the sludge of solids to discharge onto the inclined surface 48. After these solids have been thus discharged onto the surface 48 they may be easily raked toward the opening 49 in the walls of the base member 27. A manhole 50 which is provided with a suitable cover is provided also in these walls through which access to the interior of the base may be had for cleaning purposes, for inspection of valve 46, and to the covered opening 51 in the conical bottom 31. In order to strengthen the headers 11 and 12, a vertical tubular member 52 extends from the bottom header 11 to a girder 53 placed diametrically across the top of receptacle 32. Both headers 11 and 12 are secured to this tubular member which thus supports them at their centers, and through the interior of this member the chamber 30 is in communication with the atmosphere if so desired so that the filling of the chamber by the liquid to be cooled is facilitated.

Referring now to Figs. 5 and 6 the apparatus is here shown in modified form wherein the vaporizing drum 13' is placed horizontally. The tubes 14' extend between headers 11' and 12' and the liquid refrigerant distributing trays 16' instead of being generally circular in shape as shown in Figs. 1 to 4 inclusive are of rectangular shape and are of different dimensions as will be readily understood from Fig. 6.

In this form of the apparatus the liquid refrigerant from the supply 24 is discharged through the feed pipe 20' onto the uppermost distributing tray 16'. This top tray as well as all of the other trays have numerous apertures 54 therethrough which pour

continuous streams of liquid refrigerant onto the surfaces of the tubes 14'.

The surplus liquid refrigerant from each of the trays passes over the discharging lips 21' onto succeeding trays and the excess liquid refrigerant at the bottom of the tank is collected in the well 55 from which it is returned to the feed pipe 20' by means of pump 25 in the same manner as previously described.

The vaporized refrigerant passes upwardly around the ends of the staggered distributing trays 16' into a chamber 56 and is withdrawn therefrom through the pipe 23 to the liquefying apparatus also as previously described. Within the chamber 56 there are a plurality of baffle plates 57 which serve to collect any particles of liquid refrigerant which have been mechanically entrained in the vapor, and return this liquid onto the uppermost tray 16'. Therefore chamber 56 serves the same purpose as the upper portion of vaporizing chamber 13 and baffles 57 the same purpose as the uppermost tray 16 of the apparatus shown in Fig. 1.

In the modification shown in Figs. 5 and 6 the liquid to be cooled passes only once through the collecting tubes 14', no provisions having been shown for causing a continuous circulation of this liquid. Appropriate circulating apparatus or more than one pass of solution may, however, be provided if desired. As shown in Fig. 5, the liquid to be cooled preferably enters the apparatus through the pipe 58 and after passing through the cooling tubes 14' leaves through the conduit 59. Cleaning manholes 60 and 61 are arranged in the ends of the apparatus for the purpose of cleaning the interior of the tubes.

The liquid cooling apparatus of the present invention efficiently employs all of the material which enters into the construction of the apparatus. This is shown to a marked degree in the distribution of the liquid refrigerant onto the surfaces of the collecting tubes in a plurality of distributing zones so as to maintain a film of liquid refrigerant undergoing vaporization which is continuous over substantially the entire surface of the collecting tubes within the vaporizing chamber. The control of the liquid velocity in the conduits 14 by the rate of feeding or the continuous circulation of the liquid undergoing cooling provides an effective and easily controlled means for regulating the temperature of the liquid so as to produce effective and rapid cooling to the point desired, and at the same time to stop the lowering of the temperature below the required amount. This apparatus is moreover effective in the cooling of water, brine or any other liquids which it is desired to cool and is especially well adapted for cooling solu-

tions for the purpose of causing the crystallization of various materials from the solution.

I claim:

5. In a refrigerating apparatus, a vaporizing chamber for refrigerant, a plurality of conduits extending therethrough, means for passing liquid to be cooled through said conduits, a plurality of vertically spaced trays arranged within the vaporizing chamber and having outlets for distributing liquid refrigerant to the surface of said conduits, said trays each having a discharge lip for excess liquid refrigerant, said lips being in 10 staggered relation one to another so as to discharge the excess liquid refrigerant from one tray onto the next lower, and said trays acting as baffles for the vaporized refrigerant, means for supplying liquid refrigerant 15 to an upper tray, and means for withdrawing the vaporized refrigerant from said chamber.
2. In a refrigerating apparatus, a vaporizing chamber for refrigerant, a plurality of conduits therein for liquid to be cooled, means for supplying liquid refrigerant to said chamber, means for maintaining a film of liquid refrigerant on substantially the entire surface of said conduits within the chamber, means for removing vaporized refrigerant from the chamber, means for supplying liquid to be cooled to said conduits, and means for circulating said liquid repeatedly through said conduits until it is 35 cooled to the desired temperature.
3. In a refrigerating apparatus, a vaporizing chamber for refrigerant having a plurality of conduits for liquid to be cooled extending vertically therethrough, means for supplying liquid refrigerant to said chamber, means for maintaining a film of liquid refrigerant on substantially the entire surface of said conduits within the chamber, means for removing the vaporized refrigerant from the chamber, means for passing liquid to be cooled through said conduits including a receptacle beneath the vaporizing chamber for collecting solids that separate from the liquid during the cooling thereof, and means 45 for removing these solids from this receptacle.
4. In a refrigerating apparatus, a vaporizing chamber for refrigerant having a plurality of conduits for liquid to be cooled extending vertically therethrough, means for supplying liquid refrigerant to said chamber, means for maintaining a film of liquid refrigerant on substantially the entire surface of said conduits within the chamber, a pair 55 of containers for liquid to be cooled at the top of the vaporizing chamber each in communication with a portion of said conduits, a chamber at the bottom of the vaporizing chamber communicating with all of said tubes, means for supplying liquid to be 60 cooled through said conduits including a receptacle for collecting solids that separate from the liquid during the cooling thereof, and means for re-circulating said liquid.
5. In a refrigerating apparatus, a vaporizing chamber for refrigerant having a plurality of conduits for liquid to be cooled extending vertically therethrough, means for supplying liquid refrigerant to said chamber, means for maintaining a film of liquid refrigerant on substantially the entire surface of said conduits within the chamber, a pair of containers for liquid to be cooled at the top of the vaporizing chamber each in communication with a portion of said conduits, a chamber at the bottom of the vaporizing chamber communicating with all of said tubes, means for supplying liquid to be cooled through 65 said conduits including a receptacle for collecting solids that separate from the liquid during the cooling thereof, and means for re-circulating said liquid.
6. In a refrigerating apparatus, a vaporizing chamber for refrigerant having a plurality of conduits for liquid to be cooled extending vertically therethrough, means for supplying liquid refrigerant to said chamber, means for maintaining a film of liquid refrigerant on substantially the entire surface of said conduits within the chamber, means for removing the vaporized refrigerant from the chamber, means for controlling the velocity of the liquid to be cooled through said conduits, a receptacle beneath the vaporizing chamber for collecting solids that separate from the liquid during the cooling thereof, and means for removing these solids from this receptacle.
7. In a refrigerating apparatus, a cooling chamber having a plurality of conduits mounted therein, means for supplying a refrigerant to said chamber, means for passing liquid to be cooled through said conduits including a receptacle for collecting solids that separate from the liquid during the cooling thereof, and means for removing said solids from said receptacle.
8. In a refrigerating apparatus, a chamber having a plurality of conduits mounted therein, means for supplying a refrigerant to said chamber, means for passing liquid to be cooled through said conduits including a receptacle for collecting solids that separate from the liquid during the cooling thereof, and means for re-circulating said liquid.
9. In a refrigerating apparatus, a chamber having a plurality of conduits extending substantially vertically therethrough, means for supplying a refrigerant to said chamber, means for passing liquid to be cooled through 130

said conduits including a receptacle beneath said chamber for collecting solids that separate from the liquid during the cooling thereof, and means for removing said solids 5 from said receptacle.

10. In a refrigerating apparatus, a chamber having a plurality of conduits extending substantially vertically therethrough, means for supplying a refrigerant to said chamber, 10 means for passing liquid to be cooled through said conduits including a receptacle beneath said chamber for collecting solids that separate from said liquid during the cooling thereof, and means for re-circulating said 15 liquid.

11. In a refrigerating apparatus, a cham-

ber having a plurality of conduits extending substantially vertically therethrough, a receptacle positioned adjacent the bottom of said chamber and communicating with said conduits, an inlet compartment formed adjacent the top of said chamber and communicating with certain of said conduits, an outlet compartment formed adjacent said inlet compartment and communicating with others of said conduits, means for passing liquid through said conduits, and means for passing said liquid from said outlet compartment to said inlet compartment. 20

In testimony whereof I affix my signature. 25

CHARLES LALOR BURDICK.
